UNITED STATES PATENT OFFICE

2,567,920

FLOATING ROOF

John W. Allen, Chicago, Ill., assignor to Chicago Bridge & Iron Company, a corporation of Illinois

Application October 6, 1945, Serial No. 620,777

1 Claim. (Cl. 220—26)

1

This invention relates to a floating roof and more particularly to a floating roof having an annular deck portion primarily supported by a central pontoon and stabilized by an annular pontoon.

The invention is illustrated in the drawings, in which Fig. 1 is a plan view partly in section of the roof; Fig. 2 is a fragmentary sectional elevation thereof; and Fig. 3 is a sectional view taken along the line 3—3 in Fig. 1.

The roof comprises a central pontoon 11 which supports an upwardly sloping annular deck portion 12, which in turn is attached to a point well below the inner face of the annular pontoon 13.

As will be observed, the deck portion 12 is made of metal and may be made continuous with the top 14 of the central pontoon. The buoyancy of the central pontoon is made such as to provide normally an annular gas space 15 away from the center of the tank. Any suitable means of venting this space, as indicated diagrammatically at 16, may be employed.

The annular pontoon 13 is provided with an inwardly sloping upper face 17 and a vertical inner face 18 which joins the deck 12 to form a trough 19. It will be observed that all water drains toward this trough, from the center pontoon, from the deck, and from the annular pontoon. A drain 20 or a plurality of drains 20 may be provided so that any water received on the surface of the deck will flow into the liquid. Inasmuch as the center pontoon carries its own weight and that of the deck, the deck will be stable and tight and at the same time provide good drainage to the outer pontoon.

The vapor space is cut to a minimum by placing it at a point intermediate the center and the outside of the deck.

The center pontoon will carry considerable pressure under the deck without flexing so that the expansion of gases can be five or six times normal before any venting occurs under the outer pontoon.

A section 21 of the annular pontoon may be omitted adjacent the drain so that tipping will normally occur in that direction. This may readily be accomplished by omitting the bottom of the pontoon at that point and extending the deck 12 outwardly, as indicated at 12a, to join the outer face 13a of the pontoon. The adjacent space between the inner and outer faces of the pontoons is closed by a plate 25 (see Figure 3).

2

The bottom decks of the inner and outer pontoons are flat, allowing easier erection. Little or no framing is required for this purpose.

Any convenient sealing means between the outer face 13a of the annular pontoon and the side wall 26 of the tank may be employed. A continuous fabric seal 27 of elastic nature is indicated in the drawings.

It will be observed that the bottom of the annular pontoon 13 is well below the bottom of the central pontoon 11, and the top of the annular pontoon is above the top of the central pontoon.

The foregoing detailed description has been given for clearness of understanding only, and no unnecessary limitations should be understood therefrom.

What I claim as new, and desire to secure by Letters Patent, is:

A floating roof comprising a central flat bottom pontoon having a cone roof, an outer substantially annular pontoon having a downwardly and inwardly sloping upper surface forming the top wall thereof and having an inner side wall and a bottom wall, an annular upstanding rim joined to the top and bottom walls of the outer pontoon and forming the outer wall thereof, an annular deck supported entirely by the central pontoon during normal operation of the roof, said deck sloping outwardly and downwardly from the central pontoon to the annular pontoon and being connected to the inner side wall of said annular pontoon at a point substantially below the top thereof, a broken portion in the top, side and bottom walls of said annular pontoon, said deck extending at said broken portion to the outer rim and being connected thereto, and a drain at the outer edge of said deck extension.

JOHN W. ALLEN.
